UNITED STATES PATENT OFFICE.

EPHRIAM T. RUGG, OF NEWARK, OHIO.

DESIGN FOR A HALTER-RING.

SPECIFICATION forming part of Design No. 33,164, dated September 4, 1900.

Application filed July 24, 1900. Serial No. 24,724. Term of patent 14 years.

To all whom it may concern:

Be it known that I, EPHRIAM T. RUGG, a citizen of the United States, residing at Newark, in the county of Licking and State of Ohio, have invented and produced a new and original Design for a Halter-Ring, of which the following is a specification.

This invention relates to a design for a halter-ring; and the leading feature of the same consists in the design forming the subject-matter of the accompanying illustration.

The accompanying illustration represents a perspective view of a halter-ring embodying the design.

The design is characterized by the main or body portion 1, having two parallel side bars 2 and a right-angular straight bar 3 at the one end, the opposite end bar 4 having continuous oppositely-disposed converging members. Continuous with the side bars 2 are

elongated loops 5 and 6, the loop 6 having an angular position relatively to the plane of its bar and the latter provided with a pair of spurs 7. The end bar 3 also has a series of loops 8 projecting therefrom, and extending outwardly from the center of the bar 4 is a circular eye 9. From the said eye a curved member 10 extends to the end of the loop 5, to form an irregular loop 11.

Having thus described the invention, what is claimed as new is—

The design for a halter-ring, as herein shown and described.

In testimony that I claim the foregoing as my own I have hereto affixed my signature in the presence of two witnesses.

EPHRIAM T. RUGG.
